1,920,530

OIL FILLING DEVICE FOR CRANK CASES

Herbert C. Snow, Auburn, Ind., assignor to Manning & Co., Chicago, Ill., a Corporation of Illinois

Application April 9, 1930. Serial No. 442,976

7 Claims. (Cl. 220—86)

This invention relates to improvements in oil filling devices for crank cases and it consists of the matters hereinafter described and more particularly pointed out in the appended claims.

5 Engines employed in automotive vehicles and boats ordinarily include a capped tube connected to the crank case whereby lubricating oil may be introduced into said crank case. It is the custom to introduce oil in measured quantities 10 into the crank case by pouring the same into the filler tube from containers of about a quart capacity. Such containers usually include a funnel like spout for insertion into the tube after removal of the cap so that the discharge of oil from 15 the container into the spout requires considerable time and this time is increased in colder weather due to the sluggish movement of the oil.

The primary object of the invention is to provide a device which is adapted for attachment to 20 the filler tube of the engine whereby the desired quantity of oil may be substantially instantaneously dumped thereinto for flowing as it may into the crank case upon closing the cover of the device.

25 Another object of the invention is to provide a device of this kind on the order of a container adapted to have its discharge end connected to the filler tube, which device includes a valved bottom that automatically closes upon opening 30 of the cover for the introduction of the oil and automatically opens upon closing of the cover so that the oil may flow from the container down through the filler tube into the crank case.

35 A further object of the invention is to provide a device of this kind which may be readily applied to engines already in service simply by substituting the same for the cap of the filler tube.

Still a further object of the invention is to provide 40 a device of this kind which may be produced at an extremely low cost and has its parts so arranged that the device cannot readily get out of order.

45 These objects of the invention as well as others, together with the many advantages thereof will more fully appear as I proceed with my specification.

In the drawing:—

Fig. 1 is a vertical sectional view through the device with the cover in open position, ready for filling.

50 Fig. 2 is a horizontal sectional view through the device as taken on the line 2—2 of Fig. 1.

Fig. 3 is another vertical sectional view through the device as taken on the line 3—3 of Fig. 2 with the cover in a closed position.

Fig. 4 is a detail vertical sectional view as taken on the line 4—4 of Fig. 1.

In general my invention contemplates the provision of a casing, the bottom of which is formed with an angularly disposed funnel like neck for insertion in the top end of the filler tube of the engine. In the bottom end of the casing is a transverse wall having an axially disposed hole which is adapted to be opened and closed by a spring pressed valve stem. The top of the casing is provided with a hinged cover which when closed depresses the valve stem to open said hole so that oil may flow from the casing into the filler tube. When the cover is open for filling the casing, the spring pressed stem automatically closes said hole.

Referring now in detail to that embodiment of the invention illustrated in the drawing, 1 indicates as a whole an upright tubular casing having a funnel like bottom 2 which includes an angularly disposed tubular spout or neck 3. Said neck is adapted for a snug fit insertion in the top end of the filler tube 4 of an engine, which tube communicates at its bottom with the crank case of said engine. In the bottom end of said casing is provided a transverse wall 5 having an axially disposed hole 6 therein.

In the top end of said casing is a transverse cross bar 7 having one opening 8 therein arranged axially of the casing. One end 7^a of said cross bar is bent upwardly along the interior surface of the casing to be secured in place thereto by a rivet 9 having a rounded head 10 on the outside of the casing. The other end 7^b of the cross bar is also bent upwardly along the interior surface of the casing to be secured in place by a pair of rivets 11. Said rivets are also employed to secure a pair of laterally spaced ears 12 on the outside of the casing at the top thereof in line with said bar.

13 indicates an axially disposed valve stem that has sliding bearing near one end in the opening 8 of the cross bar 7 and has sliding bearing near its other end in a yoke 14 that bridges the holes 6 in the bottom wall 5 of the casing. This yoke is engaged upon a flanged spring seat 15 secured to said bottom wall about the hole 6. On the bottom end of the valve stem, below the bottom wall 5 is secured a disc valve 16, in any suitable manner. About midway between the ends of said valve stem there is mounted a cupped washer 17 that engages with a cross pin 18 in said stem. A helical expansion spring 19 surrounds that portion of the stem between the washer 17 and flanged seat 15 and normally acts to urge said

stem upwardly to hold the disc valve in a position closing the hole 6 from below.

20 indicates the cover for the open top end of the casing 1 which cover is provided at one

5 side with a boss 21 adapted to fit between the ears 12 before mentioned and to be hinged thereto by the pintle 22. Diametrically opposite said boss on the inside of the cover is secured a spring finger 23 having a bent end 24 and adjacent the

10 same is a recess 25.

Preferably but not necessarily so, I provide a bracket 26 that surrounds the casing about midway of its ends and this bracket is clamped thereto by the draw bolt 27. Said bracket terminates in laterally disposed arms 28 for attachment to any convenient place on the engine.

Assume now that the device is secured in operative relation upon an engine with its discharge neck 3 inserted in the top end of the filler tube 4

20 of said engine and it is desired to supply an additional quantity of oil to the engine. Such quantities are usually "quarts" and therefore I make the device of a capacity somewhat greater than a quart, say about one and one-tenth quarts.

25 The cover 20 is then swung into open position after releasing the finger 23 from the rivet head 10. In this opening of the cover which is swung about the pintle 22, it moves away from the top end of the stem 13 when the spring 19 will move said stem upwardly until the valve disc 16 engages the bottom wall 5 of the casing to close the hole 6 therein.

30 A quart of oil may then be poured from any suitable wide mouth container into the casing from its open top end. As the said open top end is of substantial diameter, it is apparent that this may be quickly done as there is no waiting for it to flow from a spout of relatively small cross sectional diameter. This will fill the casing to al-

35 most its top after which the cover is swung downwardly. The bent end 24 of the finger 23 will first engage the rivet head 10 and will spring or yield outwardly to pass said head when said head will spring into the recess 25 in said finger. In this

40 closing movement of the cover it will engage the top end of the stem 13 and will depress the same against the action of the spring 19 so that the disc valve 16 is moved away from the bottom wall 5 to uncover or open the hole 6. Thereafter 45 the contents of the casing drains through the same into the bottom 2 and out through the neck 3 thereof into the filler tube 4 and thence into the engine crank case to which it is connected.

50 Thus it is not necessary to wait for the oil to enter the crank case. After the casing has been charged and the cover is closed, the vehicle may at once be put under way. Thus the usual time lost at service stations waiting for the oil to flow into the crank case is saved.

55 It is pointed out that the cover is provided with a rim flange which when the cover is closed overhangs and is slightly spaced from the top edge of the casing to permit air to enter the casing as the oil flows therefrom. Again this construction provides that breather air required in the crank case.

60 The device described is simple in construction and positive in operation and there is nothing to get out of order. The casing provides a substantially wide mouth for pouring oil thereinto so that this can be quickly done without waste due to spillage.

65 While in describing the invention, I have referred in detail to the form, arrangement and construction of the various parts thereof, the

same is to be considered merely as illustrative so that I do not wish to be limited thereto except as may be specifically set forth in the appended claims.

I claim as my invention:—

80 1. A device of the kind described embodying therein a casing having an inlet end and a discharge end, the latter end being formed with a discharge neck for connection with the filler tube of an engine, a cover associated with said inlet end and a valve associated with said discharge end and movable longitudinally of the casing to close and open said discharge end upon manipulation of the cover to open and close said inlet end.

85 2. A device of the kind described comprising a casing having an open top end and a bottom end formed with a discharge neck for connection with the filler tube of an engine, a valve mechanism movable longitudinally of the casing for controlling the passage of fluid from said bottom end of the casing into said neck, a cover associated with the top end of the casing and movable to open and close the same and means associated with said valve and cover respectively and operable upon movement of the cover in opening said top end to close off said bottom end and vice versa.

90 3. A device of the kind described embodying therein a casing open at its top end and having its bottom end formed with a discharge neck for connection with the filler tube of an engine, a wall in said bottom end having a hole therein, a spring pressed stem having a valve at its bottom end normally tending to close said hole and a cover associated with the open top end of said casing for opening and closing the same, said cover when closing said top end of the casing being engaged with said stem to hold it in a position wherein its associated valve opens said hole.

95 4. A device of the kind described embodying therein a casing open at its top end and having its bottom end formed for connection with the filler tube of an engine, a wall in said bottom end having a hole therein, a spring pressed stem having a valve normally tending to close said hole, a cover hinged to the top end of said casing for opening and closing the same, said cover when closing said open top end of the casing depressing said stem to open said hole and means for releasably locking said cover in its closed position.

100 5. A device of the kind described embodying therein a casing open at its top end and having its bottom end formed for connection with the filler tube of an engine, a wall in the bottom end of said casing having a hole therein, a valve stem having guided movement in the casing, a valve on said stem below said wall, means for urging said stem in a direction wherein said valve closes said hole and a cover for said open end of the casing, arranged when closing said end to engage said stem and hold it in a position wherein the associated valve opens said hole.

105 6. A device of the kind described embodying therein a casing open at its top end and having its bottom end formed for connection with the filler tube of an engine, a wall in the bottom end of said casing having a hole therein, a valve stem having guided movement in the casing, a valve on said stem below said wall, means for urging said stem in a direction wherein said valve closes said hole and a cover hinged to said open top end of the casing at one side thereof and operable when

closed to engage and hold the valve stem in a position wherein the associated valve opens said hole and means carried upon the other side of the cover for engaging a fixed part on the cover for releasably securing said cover in its closed position.

7. A device of the kind described embodying therein a casing open at its top end and having its bottom end formed for connection with the filler tube of an engine, means providing a wall in the bottom end of the casing having a hole thereon, a stem, means providing spaced bear-

ings for said stem, one of which is associated with said bottom wall, a valve on said stem below said wall, a spring surrounding a part of said stem above said wall and acting to hold said stem in a position wherein said valve closes said hole in said bottom wall and a cover hinged to the top end of the casing and when in a position closing the same, being engaged with said stem to hold the valve in an open position with respect to said hole.
